DESIGN FOR A CAP

Samuel H. Baker, Brockton, Mass.

Application April 6, 1944, Serial No. 113,158

Term of patent 14 years

(Cl. D3—13)

To all whom it may concern:

Be it known that I, Samuel H. Baker, United States Army, a citizen of the United States, residing at Brockton, county of Plymouth, State of Massachusetts, have invented a new, original, and ornamental Design for a Cap, of which the following is a specification, reference being had to the accompanying drawings, forming a part thereof.

Fig. 1 is a side elevational view of a cap, showing my new design.

Fig. 2 is a plan view thereof.

Fig. 3 is a front elevational view thereof, and

Fig. 4 is a rear elevational view thereof.

I claim:

The ornamental design for a cap, as shown.

SAMUEL H. BAKER.
